Inventor

UNITED STATES PATENT OFFICE.

WILLIAM A. FINGLES, OF BALTIMORE, MARYLAND.

EAVES-STRIP.

SPECIFICATION forming part of Letters Patent No. 667,821, dated February 12, 1901.

Application filed December 8, 1900. Serial No. 38,938. (No model.)

To all whom it may concern:

Be it known that I, WILLIAM A. FINGLES, a citizen of the United States, residing at Baltimore, in the State of Maryland, have invented a certain new and useful Improvement in Eaves-Strips, of which the following is a specification, reference being had to the accompanying drawings.

This invention relates to an improvement in eaves-strips, and has for its object one which can be formed of a single piece with no seam-
ing, soldering, or nailing and in which it is impossible for water to back up between the wall and the sheathing in the event of the water freezing in the gutter or eaves-trough. It is also my design to so form the eaves-strip as to prevent the wind from getting under it and blowing it off, as frequently happens with the eaves-strips commonly used.

With these and other objects in view my invention consists in the peculiar arrangement and construction of parts, as hereinafter described, and then definitely set forth in the claims at the end hereof.

In the accompanying drawings, which represent the preferable embodiment of my invention, Figure 1 is a perspective view of a portion of an eaves-strip with the eaves-trough or gutter secured thereto, and Fig. 2 is a vertical section of the same.

Referring now to the details of the drawings by numerals, 1 represents the ordinary sheathing, and 2 part of the front wall, both of which are to be protected by my improvement.

3 is the sheet-metal eaves-strip, which is by preference formed at the shop, ready to be placed on the roof, and which consists of a flat and substantially horizontal portion 4, adapted to rest on top of the aforesaid sheathing 1, a locking-hook 5 being provided, to which the roof proper is connected.

At the front of the sheathing the metal is bent substantially at right angles and extends, preferably, to a distance considerably below the sheathing, so as to form a bib 6, and is then bent upwardly again, so as to be double or fold on itself, as shown at 7, when it is bent substantially parallel with the horizontal portion 4, as seen at 8, until it reaches the front wall, and is then bent downwardly at 9 a sufficient distance to protect the joint be-

tween the sheathing and front wall and to prevent the water getting or being beaten therein. The downwardly-projecting parts 55 6 and 7, forming the bib, and the protecting strip 9 form a deep inverted groove, in which the rear stem of the U-shaped eaves-trough 10 enters, as clearly shown in the drawings. The said eaves-trough is secured in position 60 by the attaching-strap 11 in the usual or any desired manner; but as this trough and its attaching means form no part of my invention further description of them is entirely unnecessary.

It is believed my invention is so simple that it needs no further description or even a statement of its use or operation, and it is clear from an inspection of my drawings that as the eaves-strip is formed of a single continuous strip it is impossible for it to leak between the sheathing and the front wall to allow water to soak through them and injure them or the inner decorated walls within. It is likewise noticeable that as no nails puncture the front vertical side water cannot get through it at this point. The bib projects into the gutter at such a position as not only to prevent the water from following the course of the strip, but it is so closely fitted over the eaves-trough as to prevent strong winds from getting under it and blowing it off the roof, and even if the wind could get a chance to act the metal forming the strip is so locked or formed around the sheathing as to obviate the necessity of nailing.

It is evident that changes in detail or the proportions of the various parts may be made without departing from the spirit of my invention.

What I claim as new is—

1. An eaves-strip made of a continuous sheet of metal formed with a recess or pocket for the sheathing, a bib projecting downwardly from near the front of said pocket and a protecting-strip projecting from near the rear of said pocket, substantially as described.
2. An eaves-strip made of a continuous sheet of metal, comprising a flat top and a downwardly-projecting front forming a bib, the metal being then continued rearwardly and downwardly, substantially as described.
3. An eaves-strip made of a continuous

sheet of metal comprising a horizontally-disposed recess adapted to receive the sheathing, and a bib and protecting-strip projecting downwardly therefrom and forming a vertically-disposed recess adapted to form a pocket or housing for the rear stem or member of the eaves-trough, substantially as described.

In testimony whereof I affix my signature, in the presence of two witnesses, this 3d day of December, 1900.

WILLIAM A. FINGLES.
